Patented Aug. 29, 1916.

FIG. 1

FIG. 2

UNITED STATES PATENT OFFICE.

CHARLES DE LUKACSEVICS AND CLAIR J. TERRILL, OF NUTLEY, NEW JERSEY; SAID TERRILL ASSIGNOR TO SAID DE LUKACSEVICS.

CARBURETER.

1,196,668.

Specification of Letters Patent. Patented Aug. 29, 1916.

Application filed May 19, 1915. Serial No. 29,150.

To all whom it may concern:

Be it known that we, CHARLES DE LUKACSEVICS and CLAIR J. TERRILL, citizens of the United States, residing at Nutley, in the county of Essex and State of New Jersey, have invented new and useful Improvements in Carbureters, of which the following is a specification.

The present invention relates to carbureters, and particularly to that type of carbureter used in connection with internal combustion engines.

The objects of the invention are, first, to produce a better mixture of the gas-vapor and air which results in better combustion; second, to produce a carbureter in which the gasolene is not atomized but given off to the mixing chamber in a gaseous form free of unvaporized liquids; and third, to produce a carbureter of novel and simple construction which will be efficient in operation.

With the above objects in view, the invention consists in certain novel features of a carbureter having a fuel chamber, an air passage in direct communication with the motor suction tube and a separating wall between the said chamber and passage which includes an absorbent element of felt or like material, exposed to and saturated 30 with the gasolene in the fuel chamber, and subject to the suction set up in the air passage incident to the action of the engine whereby gasolene will be given off as vapor to the air induced through the air passage.

55 A further feature of the invention is the provision of an improved valve in co-action with the wall which separates the fuel chamber from the air passage for regulating the quantum of the gas delivered into the air passage; and a novel relation between the said valve and a valve for controlling the air supply to the said passage, whereby the ingredients of the combustible mixture are automatically and properly proportioned.

45 An embodiment of the invention is illustrated in the accompanying drawings, wherein:

Figure 1 is a plan view of one embodiment of the invention; Fig. 2 is a vertical sectional view taken on line 2-2 of Fig. 1.

Like reference characters denote like parts throughout the specification and drawings.

A denotes a casting providing the gasolene or fuel chamber 1, and the purifying

chamber 2 at one side of the chamber 1 and separated from the latter by the angular partition 3 having an opening 4 therein for the passage of gasolene into the chamber 1. The chamber 2 is provided with the inlet 60 opening 5 having suitable connection with the gasolene tank, not shown, and is further provided with a screen or filtering means 6, supported upon the shoulder 7 in the chamber 2, for straining or purifying the gasolene of foreign matter which is apt to interfere with the proper operation of the parts of the carbureter and engine. A needle valve 8 coöperating with the opening 4 as a seat, is provided to control the flow of the 65 gasolene from the purifying chamber 2 to the chamber 1. The needle valve 8 is provided with the stem 9 slidably extended into the guide-way or cap 10 threaded in or otherwise removably secured to the casting A.

The gasolene chamber 1 is provided with a removable bottom 11 in threaded engagement therewith. The bottom 11 is formed with an annular rib 12 which defines a central opening and has its outer face 13 fashioned as a valve seat. The rib 12 provides a ledge 14 which supports co-extensive and concentric tubular members 15 and 16. A cylinder 17 of absorbent material is confined 80 by and between the members 15 and 16. The member 16 forms the wall of an air passage 20 which extends centrally through the carbureter and has its inlet at the valve seat 13; and the member 15 forms the inner 85 wall of the chamber 1, said chamber being concentric to said air passage. The member 15 is formed near its lower end with an annular row of apertures 18 through which the material 17 is exposed to the gasolene. The 90 member 16 is provided with a plurality of perforations which are preferably spirally arranged and through which the gasolene is given off from the felt 17, in gaseous form, to the air drawn through the central air passage in consequence of the suction produced by the engine. The member 16 has a flared 95 lower end which fits in an annular recess 21 formed in the bottom 11 and is frictionally retained in said recess by virtue of its own 100 resiliency.

A cylindrical valve 22 is in slidable engagement with the inner face of the member 16 and is operative to cover or expose the 105 perforations 19 and to thereby regulate the 110

amount of gas admitted into the central air passage. The valve 22 is connected by yokes 24 and 25 to an inclosed operating rod 23 having a threaded lower end 26 upon which 5 a conical air valve 29, for coöperation with the seat 13, is retained by nuts 27 and 28. The rod 23 is actuated from the shaft 35 through the arm 36 and connecting link 37, and operates the valves 22 and 29 in unison, 10 whereby the gas and air are properly and automatically proportioned for any quantum of fuel mixture within the capacity of the carbureter.

The valve 29 comprises a section 29^a forming the valve face and slidable upon the rod 23. A spring 30 surrounds the rod 23 and bears against the nut 28, exerting tension upon the valve section 29^a, the upward movement of which is limited by the nut 27. The 15 valve face or section 29^a has a back or reinforcing section 29^b in suitable engagement therewith. It is to be understood that the nuts 27 and 28 are adjustable upon the threaded portion 26 of the rod, thereby permitting any desired adjustment of the air valve 29; the purpose of this construction of the valve being presently set forth:

Fig. 1 illustrates the carbureter with its parts in inoperative relation, the perforations 19 being closed, while the valve 29 is so adjusted as to permit a slight inflow of air into the passage 20. For priming, or when it is desired to start the engine, not shown, the rod 23 is operated to close the 20 valve 29 firmly upon its seat 12, and to raise the sleeve 22 until it uncovers the lowermost row of openings 33', thus cutting off all air supply to the passage 20, and allowing a charge of pure gaseous vapor to be carried 25 to the engine. It will be seen that since the valve 29 is slidably mounted on the rod 23, the spring 28 will compensate for any increased upward movement of the rod 23 and firmly seat the valve 29 upon the valve seat 12. However, under normal running conditions, the sleeve 29 is operated to admit air 30 to the passage 20 and the sleeve valve 22 is operated as to uncover the perforations 19.

In many of the carbureters heretofore constructed wherein atomizing and spraying means are employed for vaporizing liquid fuel, a certain quantity of the liquid fuel passes into the machine unvaporized and the moisture incident to this unvaporized 35 liquid causes an imperfect and delayed combustion, as well as producing carbon in the engine cylinder. It will be obvious from the above construction that applicants overcome this disadvantage by providing means 40 for absorbing the liquid fuel and which gives the fuel off and permits the same to evaporate therefrom in a gaseous form free of liquid and moisture. The vaporized gas thus obtained, also, admits of a better 45 mechanical mixing with the air.

A mixing chamber 39 is provided for the carbureter and comprises a hollow member of a gradually increasing diameter, having an annular flange projecting laterally therefrom intermediate its ends provided upon 70 its edges with a threaded portion. When the carbureter is assembled, the reduced end of the mixing chamber 39 is inserted and lies between the upper or inner extremities of the tubular members 15 and 16, while the 75 annular flange 40 which provides a top or cover for the chamber 1 is threaded upon the upper edge of said chamber. An annular float 41 is pivotally disposed in the chamber 1 and surrounds the tubular member 15. Extending rearwardly of the pivot 42 of the float is the spherical projection 43 adapted to engage a reduced portion in the needle valve stem 9. Thus, it will be seen that upon the rise and fall of the float 42 80 the needle valve 8 will be operated to open and close the opening 4 in the partition 3 and control the supply of liquid fuel to the chamber 1. The chambers 1 and 2 are formed with drain outlets 1^a and 2^a, respectively, which are adapted to be closed by a screw-threaded plug or other suitable means. The chamber 2 is also provided with a screw cap 2^b which permits the insertion and removal of the screen or filtering member 5. 95 It will also be obvious that upon removing bottom 11 of the chamber 1, the absorbent material disposed between the tubular members 15 and 16 may be replaced, when occasion requires, and access to the sleeve valve 100 22 and air valve 29 may be had.

An air duct 31 is suitably attached to the bottom 11 for directing air to the air inlet 12. The air duct 31 is provided with a plurality of supplemental air inlets 32 controlled by the manually operated ring 33. The lower end of the rod 23 extends into the wall of the air duct 31, as shown at 34, which thus provides an additional guiding 105 means for the rod.

What is claimed is:—

1. A carbureter having a fuel chamber, a central air passage to which the fuel chamber is concentric, a wall separating the fuel chamber and the air passage throughout their extent and including a felt absorbent element projecting toward the base of said fuel chamber and means for retaining said absorbent element in position, constructed to expose said element at one side thereof to the gasoline in said fuel chamber and at the other side to the air flowing through said passage, said passage having an annular air inlet at one end and being open to the motor suction tube at its other end, a cylindrical valve working within said passage and along the inner face of said wall and operative to regulate the degree to which the absorbent element is exposed to the air, and a second valve connected to said 110 115 120 125 130 135 140 145 150 155 160 165 170 175 180 185 190 195 196 197 198 199 200

cylindrical valve for movement therewith and controlling the said annular air inlet, the connection between said valves including a resilient element for permitting a movement of said cylindrical valve in a direction away from said inlet, while the second valve is held closed on its seat.

2. A carbureter having a fuel chamber, a cover therefor, a central air passage to which the fuel chamber is concentric, and an annular wall separating the fuel chamber and air passage throughout their extent and comprising an annular part formed with said cover, concentric tubular members extending between said annular part

and the base of said fuel chamber and formed with perforations at intervals throughout their extent, and a cylinder of absorbent material arranged between said tubular members and between said annular 20 part and the base of said fuel chamber.

In testimony whereof we have hereunto set our hands in presence of two subscribing witnesses.
